UNITED STATES PATENT OFFICE.

CLARENCE B. FOSTER, OF GLENDALE, CALIFORNIA, ASSIGNOR OF ONE-SIXTH TO FREDERICK L. FEISTHAMEL, ONE-SIXTH TO ARTHUR J. CARR, AND ONE-SIXTH TO THOMAS A. COLLINS, ALL OF LOS ANGELES, CALIFORNIA.

FABRICATED DERRICK.

Application filed July 17, 1926. Serial No. 123,137.

This invention relates to improvements in fabricated derricks, and is particularly directed to the general class of derrick structures usually employed in the drilling and 5 operating of oil, gas and like wells.

More specifically, the present invention is directed to certain improvements in the construction of the type of panel derrick disclosed in my co-pending application Serial 10 No. 123,136, and has for an object to provide an improved method of constructing the several panels, adapting them for connection to the adjacent panels at the corners of the derrick independently of the removable 15 corner leg members, so as to provide a derrick structure which will be self sustaining before said corner leg members are applied or after they are removed and without it being necessary to apply substitute corner 20 connections or joint plates, although such substitute corner connections may be applied for additional strength, if desired.

Another object is to so connect the adjacent panels as to provide a more stable 25 structure, especially against horizontal and torsional strains.

A further object is to provide a structure which may be easily and quickly erected to form a heavy duty drilling derrick, and 30 which may subsequently be readily and quickly converted to a lighter derrick suitable for use as a pumping derrick.

Various other objects and advantages will be more fully apparent from the following 35 description of the accompanying drawings which form a part of this disclosure, and which illustrate a preferred form of embodiment of the invention.

Of the drawings:

Fig. 1 is an elevation of a drilling derrick constructed in accordance with the present invention.

Fig. 2 is an enlarged plan section, partly broken, taken on line 2—2 of Fig. 1.

Fig. 3 is a fragmentary perspective of a corner of the derrick viewed as indicated by the arrow 3 in Fig. 2.

Fig. 4 is partial vertical section taken on line 4—4 of Fig. 2.

Fig. 5 is a plan section taken on line 5—5 of Fig. 4.

Fig. 6 is an elevation of one of the panel sections.

Fig. 7 is a plan section, similar to Fig. 2, showing the substitution of the joint plates 55 for the corner leg members when the construction is converted to constitute a pumping derrick.

Fig. 8 is a perspective view, similar to Fig. 3, of a corner of the pumping derrick. 60

Fig. 9 is a fragmentary plan section illustrating a modified form of construction, and

Fig. 10 is a fragmentary perspective view of the construction shown in Fig. 9 and viewed as indicated by the arrow 10 therein. 65

As illustrated in the drawings, each of the four sides of the derrick is formed of a plurality of panel sections secured together in vertical alignment, with the several panel sections of suitable dimensions to produce a 70 completed derrick gradually tapering upwardly to the top upon which will be mounted the usual crown block.

The respective panels of each side may be exact duplicates of those of the other three 75 sides and in the erection of the derrick the panels are arranged in tiers or stories one upon the other with the four panels of each tier horizontally aligned, thus permitting all four panels of each tier being of the same 80 relative size so they may be interchangeable as well as readily adaptable for standardization.

With this construction each tier is finished to a horizontal level thus eliminating the 85 necessity of providing two short panels at the bottom and top of the derrick as is required in a panel derrick in which the panels of adjacent sides are arranged in break-joint relationship. 90

While the several panels of the derrick are herein described as being of duplicate character, this has more particular reference to the major portion of the derrick, it being evident to those skilled in the oil industry 95 that the lower panels will necessarily be somewhat modified to accommodate the walking-beam, draw-works and other portions of the drilling or pumping equipment and also that suitable provisions will be made 100 for the derrick ladder, platform, water-table and crown-block, etc.

2

The several panels are of the construction shown in Fig. 6 of the drawings, each panel including opposite marginal angle side members 11 and 12 disposed vertically and at a slightly converging angles corresponding to the general taper of the completed derrick, lower and upper transverse marginal girts 13 and 14, an intermediate transverse girt 15, a lower pair of diagonal sway braces 16 and 17, an upper pair of similar diagonal sway braces 18 and 19, and lower and upper vertical hangers 20 and 21. The marginal side members 11 and 12 are arranged with their respective flanges 11^a and 12^a disposed towards each other in the plane of the panel and with their respective adjacent flanges 11^b and 12^b extended outwardly, and the respective lower and upper transverse marginal girts 13 and 14 are arranged with their respective vertical flanges disposed towards each other in the plane of the panel and with their respective horizontal flanges extended inwardly.

All of the girts and sway braces are preferably of angle form and the ends of the several sway braces may be swaged to bring both of the flanges thereof to parallel contact to provide securing ends of double thickness, while the ends of the girts are not so swaged but have their respective horizontal flanges cut at 45° angles, as shown in Figs. 2, 3, 5, and 7. The ends of the sway braces, the vertical flanges of the girts and the flanges 11^a and 12^a of the respective marginal side angles 11 and 12 are suitably punched or bored to receive securing rivets or bolts, the several rivets securing the parts of the panel together being designated by reference characters consisting of a suffix 40 added to the numeral designating the respective parts they secure to the side angles 11 and 12, thus the rivets 13^a secure the transverse girt 13 to the lower ends of the side angles 11 and 12, the rivets 14^a secure 45 the transverse girt 14 to the upper ends of said side angles, while the rivets 15^a, 16^a, 17^a, 18^a, and 19^a, respectively secure the intermediate girt and the several sway braces to said side angles.

50 While it is evident and is clearly realized that the derrick may, if desired, be erected piece by piece, the preferred method to be followed in practice will be to preassemble the several panels, leaving to the field crew 55 only the work of assembling these panels into a complete derrick. Therefore, I will for the purpose of this disclosure, limit the description of the erection to the manner in which the several panels and their cooperating parts are secured together to form the completed structure, it being understood that the erection of the several tiers will be progressive from the bottom to the top of the structure, and further that the panels of 60 each tier will rest upon the like panels of

the next lower tier with the horizontal flanges of their lower transverse marginal girts 13 contacting the horizontal flanges of the transverse marginal girts 14 of said next lower panels (see Fig. 4).

70 Also, at this same level the side angles 11 and 12 of the panels of each tier will abut upon the aligned side angles of the panels of the next lower tier so that insofar as the panels themselves are concerned those of 75 every tier are horizontally aligned.

In the erection of the derrick, the four panels of a tier will be positioned upon those of the next lower tier and the horizontal flanges of their lower marginal girts 13 will be secured at suitable intervals to the adjacent horizontal flanges of the upper marginal girts 14 of said next lower tier by bolts 22, (see Figs. 2 and 4). These marginal girts 13 and 14 are further secured 80 together near each corner of the derrick and connected to those of the adjacent panels by gusset plates 23 and bolts 24 (see Figs. 2 and 4), said gusset plates being respectively positioned above and below the horizontal flanges of said girts and the bolts 24 securing said flanges and gusset plates rigidly together. In a somewhat similar manner the intermediate girt 15 of each panel in a tier is joined to the like intermediate girts 85 of the panels of the adjacent sides of the derrick by gusset plates 26 and bolts 27 (see Figs. 4 and 5). Thus the several panels of 90 each tier are connected together at the corners of the derrick and the panels of each tier are also connected to those of the next lower and upper tiers independently of any corner posts or leg members.

To complete the derrick for use as a heavy duty drilling derrick there will be provided 105 angle corner posts or legs which extend throughout the full height of the several tiers at the four corners, said corner legs each preferably consisting of a plurality of angle sections 28 abutting each other end on end and positioned between and in intimate contact with the respective side angles of the adjacent panels, the respective flanges of said leg sections 28 being secured to the flanges 11^b and 12^b of said panel side angles 115 at intervals throughout their lengths by bolts 29, 30, and 31. It will be noted that the several angle sections 28 of each corner leg are preferably of uniform length and are arranged so that they break joint with 120 the several tiers, that is, the line 32 of abutment between the vertically adjacent leg sections is opposite the intermediate girts 15 of the adjacent tier. This brings the 125 leg angle sections in vertically staggered relationship with the side angles of the panels.

The above described construction provides a derrick having all of its sides constructed of complete pre-assembled panels, with the panels of the several sides arranged 130

in superposed tiers and with all of the panels of each tier horizontally aligned and of the same size and character and interchangeable one with another. Such a construction 5 provides a derrick of great strength coupled with extreme relative lightness of the material required for its manufacture.

A feature of major importance incident to the construction above described, is its 10 adaptability for conversion to a derrick of lighter construction capable of use as a pumping derrick. This can be very easily and quickly accomplished by removing the corner leg sections 28 and replacing them 15 with short angle joint-plates 33 (see Figs. 7 and 8) positioned adjacent the abutting ends of the side angles 11 and 12 of the adjacent panels and secured thereto by bolts 34, these bolts extending through the same 20 bolt holes in said side angles as did the previously described bolts 29. The leg sections 28 so removed will constitute a very appreciable amount of salvage and can be subsequently utilized to recondition the derrick 25 as a drilling derrick or can be incorporated in a new derrick structure.

If thought desirable, additional joint-plates 35 may be secured adjacent the respective intermediate girts by bolts 36 which 30 extend through the same bolt holes as did the previously described bolts 31.

In Figs. 9 and 10 there is illustrated a modified form of structure in which the angle side members of the panels have their 35 flanges 37 extended inwardly and joined to the corner leg sections, or joint-plates as the case may be, by bolts 38, the horizontal flanges of the transverse girts being connected by gusset plates 40 and bolts 41.

40 While the structure herein illustrated and described is fully capable of fulfilling all of the objects primarily stated it is to be understood that I do not wish to restrict the present invention to the specific embodiment 45 in various other forms all coming within the scope of the claims, which follow.

I claim as my invention:

1. In a derrick of the nature disclosed, the 50 combination of: adjacent sides each formed of a plurality of vertically aligned complete pre-assembled panel sections, with the panel sections of each side laterally spaced from those of the adjacent sides; intermediate 55 corner legs disposed at the respective corners of the derrick and positioned between the horizontally adjacent panel sections; means for securing said legs to said panel sections to connect the sides of the derrick together; and means for connecting the panel sections of the adjacent sides independently of the intermediate corner legs.

2. In a derrick of the nature disclosed, the 60 combination of: adjacent sides each formed of a plurality of vertically aligned complete

pre-assembled panel sections, with the panel sections of each side laterally spaced from those of the adjacent sides and with the panel sections of the several sides horizontally aligned in superposed stories or tiers; intermediate corner legs disposed at the respective corners of the derrick and positioned between the horizontally adjacent panel sections; means for securing said legs to said panel sections to connect the sides of the 70 derrick together; and means for connecting the panel sections of the adjacent sides independently of the intermediate corner legs.

3. In a derrick of the nature disclosed, the combination of: adjacent sides each formed of a plurality of vertically aligned complete pre-assembled panel sections, with the panel sections of each side laterally spaced from those of the adjacent sides and with the panel sections of the several sides horizontally aligned in superposed stories or tiers; intermediate connecting corner elements disposed at the respective corners of the derrick and positioned between the horizontally adjacent panel sections and in 80 break-joint relationship thereto; means for securing said elements to said panel sections to connect the sides of the derrick together; and means for connecting the adjacent sides independently of the intermediate 85 corner elements.

4. In a derrick of the nature disclosed, the combination of: adjacent sides each formed of a plurality of vertically aligned complete pre-assembled panel sections, with the panel sections of each side laterally spaced from those of the adjacent sides, each panel section having opposed marginal side angles and transverse girts connecting said side angles; intermediate angle corner legs disposed at the respective corners of the derrick and positioned between the side angles of the horizontally adjacent panel sections; means for securing said angle corner legs to the associated panel sections to connect the 100 sides of the derrick together, the side angles of the adjacent panel sections and the associated angle corner legs being arranged in back-to-back relationship to form at each corner of the derrick, a corner column substantially cross-shape in cross section; and means for connecting the adjacent sides independently of the intermediate angle corner legs.

5. In a derrick of the nature disclosed, the 110 combination of: adjacent sides each formed of a plurality of vertically aligned complete pre-assembled panel sections, with the panel sections of each side laterally spaced from those of the adjacent sides and with the panel sections of the several sides horizontally aligned in superposed stories or tiers, each panel section having opposed marginal side angles and transverse girts connecting said side angles; intermediate corner legs 115 120 125 130

disposed at the respective corners of the derrick and positioned between the side angles of the horizontally adjacent panel sections, each corner leg being comprised of a plurality of vertically aligned leg angles arranged in break-joint relationship to the respective stories or tiers; means for securing the leg angles to the associated panel sections to connect the sides of the derrick together, the side angles of the adjacent panel sections and the associated corner leg angles being arranged in back-to-back relationship to form at each corner of the derrick, a corner column substantially cross-shape in cross section; and means for connecting the horizontally aligned girts of adjacent sides of the derrick, independently of the corner leg angles.

6. In a derrick of the nature disclosed, the combination of: adjacent sides each formed of a plurality of vertically aligned complete pre-assembled panel sections, with the panel sections of each side laterally spaced from those of the adjacent sides, each panel section having opposed marginal side angles and transverse girts connecting said side angles with said girts secured at opposite ends to one flange of each of said side angles; intermediate angle corner legs disposed at the respective corners of the derrick and positioned between the side angles of the horizontally adjacent panel sections; means for securing said angle corner legs to the other flanges of the associated panel sections to connect the sides of the derrick together, the side angles of the adjacent panel sections and the associated angle corner legs being arranged in back-to-back relationship to form at each corner of the derrick, a corner column substantially cross-shape in cross section; and means for connecting the adjacent sides of the derrick independently of the intermediate corner legs.

7. In a derrick of the nature disclosed, the combination of: adjacent sides each formed of a plurality of vertically aligned complete pre-assembled panel sections, with the panel sections of each side laterally spaced from those of the adjacent sides and with the panel sections of the several sides horizontally aligned in superposed stores or tiers, each panel section having opposed marginal side angles and transverse girts connecting said side angles with said girts secured at opposite ends to one flange of each of said side angles; intermediate corner legs disposed at the respective corners of the derrick and positioned between the side angles of the horizontally adjacent panel sections, each corner leg being comprised of a plurality of vertically aligned leg angles arranged in break-joint relationship to the respective stories or tier; means for securing the leg angles to the other flanges of the associated panel sections to connect the sides of the derrick together, the side angles of the adjacent panel sections and the associated angle corner legs being arranged in back-to-back relationship to form at each corner of the derrick, a corner column substantially cross-shape in cross section; and means for connecting the horizontally aligned girts of adjacent sides of the derrick, independently of the corner leg angles.

rick together, the side angles of the adjacent panel sections and the associated angle corner legs being arranged to form at each corner of the derrick, a corner column substantially cross-shape in cross section; and means connecting the girts of each side with the corresponding girts of the adjacent sides independently of the leg angles.

8. In a derrick of the nature disclosed, the combination of: adjacent sides each formed of a plurality of vertically aligned complete pre-assembled panel sections, with the panel sections of each side laterally spaced from those of the adjacent sides and with the panel sections of the several sides horizontally aligned in superposed stores or tiers each extended to a horizontal level, each panel section having opposed marginal side angles and lower and upper transverse marginal girts connecting said side angles with said lower transverse girt secured at opposite ends to the respective lower ends of said side angles and with said upper transverse girt secured at opposite ends to the respective upper ends of said side angles; intermediate angle corner legs disposed at the respective corners of the derrick and positioned between the side angles of the horizontally adjacent panel sections; means for connecting the lower transverse girt of each panel section of each side of the derrick to the upper transverse girt of the next lower panel section; independent means for securing the angle corner legs to the associated panel sections to connect the sides of the derrick together, the side angles of the adjacent panel sections and the associated angle corner legs being arranged in back-to-back relationship to form at each corner of the derrick, a corner column substantially cross-shape in cross section; and means for connecting the respective lower and upper transverse girts of each side of the derrick to the corresponding lower and upper transverse girts of the adjacent sides thereof, independently of the intermediate corner legs.

9. In a derrick of the nature disclosed, the combination of: four independent sides each formed of a plurality of superposed panel sections with each panel sections secured to the vertically adjacent panel sections; a separate corner leg at each respective corner of the derrick, disposed between the adjacent sides thereof and secured to the several panel sections comprising said adjacent sides to join said sides to each other; and separate means for connecting the adjacent sides of the derrick together, independently of the corner legs, whereby said corner legs may be removed at any time, leaving a self sustaining derrick structure.

10. In a derrick of the nature disclosed, the combination of: adjacent sides each formed of a plurality of vertically aligned

- complete pre-assembled panel sections, with the panel sections of each side laterally spaced from those of the adjacent sides, each panel having opposed marginal side angles 5 and transverse angle girts connecting said side angles with the vertical flanges of said girts secured at opposite ends to one flange of each of said side angles, the girts associated with each side of the derrick being 10 horizontally aligned with the like girts of the adjacent sides; intermediate angle corner legs disposed at the respective corners of the derrick and positioned between the side angles of the horizontally adjacent panel sections; means for connecting the lower transverse 15 girt of each panel section of each side of the derrick to the upper transverse girt of the next lower panel section; independent means for securing the angle corner legs to the associated panel sections to connect the sides 20 of the derrick together; the side angles of the adjacent panel sections and the associated angle corner legs being arranged in back-to-back relationship to form at each corner of the derrick, a corner column substantially cross-shape in cross section; and horizontal gusset plates connecting the horizontal flanges 25 of the angle girts of each side of the derrick to those of the adjacent sides, independently of the angle corner legs.
11. In a derrick of the nature disclosed, the combination of: adjacent sides each 30 formed of a plurality of vertically aligned complete pre-assembled panel sections, with the panel sections of each side laterally spaced from those of the adjacent sides and with the panel sections of the several sides 35 horizontally aligned in superposed stories or tiers each extended to a horizontal level,
- each panel section having opposed marginal side angles and lower and upper transverse marginal girts of angle form connecting said side angles with the vertical flange of said lower transverse girt secured at opposite ends to the respective lower ends of said side angles and with the vertical flange of said upper transverse girt secured at opposite ends to the respective upper ends of said side 40 angles; intermediate angle corner legs disposed at the respective corners of the derrick and positioned between the side angles of the horizontally adjacent panel sections; means for connecting the lower transverse 45 girt of each panel section of each side of the derrick to the upper transverse girt of the next lower panel section; independent means for securing the angle corner legs to the associated panel sections to connect the sides 50 of the derrick together; the side angles of the adjacent panel sections and the associated angle corner legs being arranged in back-to-back relationship to form at each corner of the derrick, a corner column substantially cross-shape in cross section; and horizontal gusset plates connecting the horizontal flanges 55 of the respective lower and upper transverse girts of the panel sections of each side of the derrick to the horizontal flanges of the like girts of the adjacent sides, independently of the angle corner legs.
- In testimony whereof, I have hereunto set my hand at Los Angeles, California, this 8th 60 day of July, 1926.
- CLARENCE B. FOSTER.
